RIBBON REVERSING MECHANISM FOR
WRITING MACHINES

James Marshall Stolz, Los Angeles, Calif.

Application March 7, 1946, Serial No. 652,752

2 Claims. (Cl. 197—165)

(Granted under the act of March 3, 1883, as
amended April 30, 1928; 370 O. G. 757)

1

The invention described herein may be manufactured and used by or for the Government for governmental purposes, without payment of any royalty thereon.

This invention is in typewriting machines and more specifically is an automatic ribbon reverse.

In certain kinds of typewriting machines, particularly those utilizing a driven type wheel instead of the customary individual type bars, no means is provided for the automatic reversal of the inked ribbon when it has become completely wound upon one spool, and manual reversal is necessary. Several disadvantages arise from this condition. Frequently, an operator will reverse the ribbon well before the proper time, and this results in nonuse of a substantial portion thereof. On the other hand, an operator in some cases may fail to note that reversal is necessary; the machine then types on one part of the ribbon only, reducing the clarity of the printed matter and perhaps wearing a hole in the ribbon. In extreme cases, breakage of the ribbon occurs.

The principal object of this invention is to provide a novel means for automatically reversing the ribbon in a typewriting machine of the nature indicated so as to eliminate the aforementioned difficulties.

Other objects will be apparent from a reading of the following specification and claims.

The single drawing is a front view, partly broken away, of the ribbon reversing mechanism of my invention.

Referring to the drawing, the typing and ribbon winding elements—in themselves substantially conventional—may be seen to include a typewheel 10 having numerals, letters and other indicia on the periphery thereof, the typewheel being adapted to be driven by a power source (not shown), two ribbon spools 11 and 12, provided with toothed driving wheels, as 11' and 12', respectively, and an arm 15 having two teeth 15' and 15'', the first being adapted to cooperate with wheel 11' and the second with toothed wheel 12'. Arm 15 is driven through an eccentric by the same power source which drives print wheel 10; its action is to engage the toothed wheels 11' and 12' and to wind the ribbon 20 first in one direction and then in the other.

In a construction of this nature, difficulty is encountered with any arrangement which depends for shifting arm 15 upon the strain which gradually builds up in the ribbon when the ribbon is run completely off one spool since the first action is to move arm 15 out of engagement with

2

its cooperating ratchet wheel and thus prevent further advance of the ribbon.

Briefly, my invention provides means for preventing any movement of arm 15 until enough strain has been accumulated to snap the arm quickly to its second operative position, namely (according to the drawing), in engagement with ratchet wheel 12'.

According to my invention, the ribbon 20 is threaded through the apparatus in substantially conventional manner, as from spool 11, through guides 21, 22, and 23, and to spool 12. Guide 22, it will be understood, is furnished with an opening 22' through which a hammer (not shown) may cooperate with typewheel 10 to cause a character to be printed.

Assuming that the parts are in the conditions shown in the drawing, the ribbon being almost completely wound upon spool 11, the eyelet 30, which is located adjacent the end of ribbon 20, 10 will catch in the guide 23. As ratchet wheel 11' continues to step, lever 31, pivoted at 32, will move under the urging of eyelet 30 and abut against lever 33, pivoted at 34. Movement of lever 31, therefore, first increases the tension on spring 35 and then, acting through lever 33, moves pin 36, normally bearing against plate 37 above the corner 39 of said plate. It is this pin which prevents premature movement of arm 15. The parts 20 are so calculated that by the time pin 36 clears plate 37 spring 35 is under sufficient tension to move arm 15 rapidly into engagement with ratchet wheel 12', notwithstanding the restraining influence of spring 40.

35 At the same time, pin 45, urged by spring 46, shown in the drawing as beneath the lower edge of plate 37, moves into a position substantially like that previously occupied by pin 36 but against the opposite side of plate 37.

40 The operations are then repeated except that ratchet wheel 12' is rotated by tooth 15'' of arm 15 and the ribbon wound upon spool 12.

The foregoing description is in specific terms, and many modifications will suggest themselves.

45 For the true scope of the invention, reference should be had to the appended claims.

I claim:

1. In a ribbon reversing mechanism for a writing machine, including two ribbon spools and a ribbon having elements adjacent the ends thereof of substantially greater thickness than the ribbon, two ratchet wheels each adapted to drive one of said spools, a ratchet adapted to drive said wheels alternately, and means for controlling said ratchet including a pivoted lever having a

ribbon guide thereon adapted to be engaged by one of said thickened elements, continued movement of the ribbon after such engagement resulting in movement of said lever upon its pivot, a spring associated with said lever and with said ratchet, said spring being adapted to have its tension increased by movement of said lever, and a second lever adapted when in one position to bear against said ratchet, said second lever being adapted to be moved out of engagement with said ratchet by said first lever after a predetermined movement of said first lever.

2. In a ribbon reversing mechanism for a writing machine, a first ribbon spool, a first ratchet wheel for driving the same, a second ribbon spool, a second ratchet wheel for driving the same, a ratchet having one normal position in engagement with the first ratchet wheel and a second normal position in engagement with the second ratchet wheel, and means for shifting said ratchet from each of said normal positions to the other including a first lever and a second lever, a first spring connecting said first lever and said ratchet, a second spring connecting said second lever and said ratchet, said levers being adapted to be put under strain by means adjacent the end of a ribbon, said springs being

10
5

adapted to have their tension increased by the lever associated therewith as the same is put under strain, a first member and a second member, each having two normal positions and each adapted to prevent disengagement of said ratchet when in one of its normal positions, said members being adapted to be moved to their second normal positions by said levers after their cooperating springs have been tensioned.
